(57) CLAIM

The ornamental design for pants, substantially as shown and described.

DESCRIPTION

FIG. 1 is a front elevation of pants drawn partially in fragment showing my new design;

FIG. 2 is a rear elevation thereof;

FIG. 3 is a right side elevation view thereof;

FIG. 4 is a left elevation view thereof;

FIG. 5 is a top plan view thereof;

FIG. 6 is a cross-section thereof, taken along line 6—6 in FIG. 5 and shown in fragment and on a slightly enlarged scale; and,

FIG. 7 is a bottom plan view thereof.

The texture shown on the waistband area represents color contrast. The broken lines shown around the pockets and seams represent conventional stitching. The broken lines on the bottom edge of the design and shown at the lower areas in FIGS. 3 through 5 and 7 show environment and form no part of the claimed design.
